UNITED STATES PATENT OFFICE.

LOUIS FEY, OF CINCINNATI, OHIO.

BROILER.

No. 928,348.

Specification of Letters Patent.

Patented June 1, 1909.

Application filed March 25, 1909. Serial No. 485,566.

To all whom it may concern:

Be it known that I, LOUIS FEY, a citizen of the United States, residing at Cincinnati, in the county of Hamilton and State of Ohio, have invented certain new and useful Improvements in Broilers, of which the following is a specification.

My invention relates to burners, and its object is to provide an arrangement of burners for using gaseous fuel in broiling meats and the like by placing the articles to be broiled over the burners, thereby utilizing the full amount of heat produced, and at the same time to avoid ignition of the grease or juices from the articles broiled, and avoid the clogging of the burner orifices.

My invention consists in the combination with a burner having orifices for the escape and combustion of gaseous fuel, of a shield or hood mounted on the burner, having arches over said orifices through which the flames of combustion may pass from the orifices, but by means of which fluid matter is carried below the burner without ignition.

My invention also consists in the parts and in the construction and arrangement of parts as will hereinafter be described.

In the drawings: Figure 1 is a front elevation of a device embodying my invention. Fig. 2 is a horizontal cross section on the line $x-x$ of Fig. 1. Fig. 3 is a vertical cross section on a line corresponding to the line $y-y$ of Fig. 1, extending from the front to the rear of the device. Fig. 4 is a vertical cross section on a line corresponding to the line $z-z$ of Fig. 2, illustrating, however, a modification of the use of the device. Figs. 5 and 6 are, respectively, a plan view and a side elevation of part of the hood. Fig. 7 is a vertical cross section through the hood on the line $a-a$ of Fig. 6. Fig. 8 is a cross section on the line $b-b$ of Fig. 6. Fig. 9 is a section longitudinally of the hood through one of the arches on a line corresponding to the line $c-c$ of Fig. 5. Fig. 10 is a similar section on a line corresponding to the line $d-d$ of Fig. 5. Fig. 11 is a vertical section through a hood and a burner longitudinally thereof, illustrating a modification of the burner to receive the hood, parts being broken away for lack of space. Fig. 12 is a similar section, through part of a hood and burner formed integral. Fig. 13 is a side elevation of a hood in which wires are used for legs, parts being broken away for lack of space. Fig. 14 illustrates the operation of

the two forms of legs shown, in conducting liquid.

As illustrated in the drawings, the broiler consists in a casing 1, provided interiorly with ledges 2, on opposite sides, running horizontally from its front to its rear, on which may be supported, at various heights, a broiler grating 3, which is adapted to receive meats or other articles to be broiled. Below the grating 3 are the burners 4, each consisting in a tube closed at one end by a cap 5 and communicating through its other end with a mixer of suitable construction, which receives the gas through a pipe 7 provided with a valve 8 for controlling the flow of the gas to the burner. A main valve 9 controls the flow of gas to all the burners. These tubes forming the burners 4 extend transversely of the casing, at, preferably, regular intervals, and are provided with orifices 10 at regular intervals throughout the greater part of their lengths, the orifices being located on both sides and extending radially through the walls of the tubes at angles suitable to direct the flames upward against the lower side of the articles being broiled, in the most effective manner.

Resting on the tube is the shield or hood consisting in a series of arches 11, each of which is so positioned that one of the orifices 10 will be located within it. At the same time, the hood, thus made up of the arches, straddles the tube and thus rests thereon in such position that the tops of the arches are maintained a considerable distance above the upper side of the tube, and the hood is otherwise so proportioned that the flames coming from the orifices 10 may pass upwardly, as above stated, through the arches without being obstructed thereby. The tops of the arches, which form the greater part of the mass of the hood or shield, by this construction, are also prevented from being excessively heated, owing to the fact that none of the flames strike them directly, thus adding to the lasting qualities of the device. Owing to the construction of the hood in the form of a series of arches succeeding each other lengthwise of the tube and straddling the tube, the part of the hood between each arch on each side will form a leg 12. Each of these legs 12 is provided with a vertically extending groove, or gutter 13, and laterally downwardly sloping gutters 14 are provided between the arches, on the top of the hood, communicating with these vertically ex-

tending gutters 13. The top of each arch is inclined from a middle horizontal ridge 15, in both directions to these gutters 14 between the arches. It will thus be seen that 5 the top of the arch over the orifice in the burner, extending in a horizontal direction, will not be adapted to conduct the grease over the side of the hood at the top of the arch, but all liquids will be conducted into 10 the gutters 14 and from there into the gutters 13 in the legs 12 between the orifices and between the flames which escape therefrom. In addition to being thus constructed, the hoods are so positioned that adjacent ones 15 will be out of alinement to the extent of one-half the width of one of the arches so that the flame passing from the orifices in one burner will pass diagonally upward and over the gutters 13 and 14 of the adjacent hood. 20 Thus, ample space is allowed for the passage of the flames to avoid interference as hereinbefore referred to.

As preferred, the hoods are formed separately from the burners and secured thereon 25 by means of nuts 16 screwed onto the tube of the burner at the ends, clamping the hood between them. It will be seen that the position of each hood on its respective burner may be adjusted by screwing the nuts forward or backward on the tube. In order to 30 maintain the hood positively in upright position on the tubular burner, I prefer to provide the burner with lugs 17 near its ends which are adapted to enter corresponding 35 recesses 18 in the lower sides of the arches at the ends of the hood. Where adjustment of the hood longitudinally of the burner is not considered essential, the burner may be formed with hubs 19 at its ends adjacent to 40 which it is provided with lugs 17^a adapted to enter recesses 18 in the hood, as above described.

In the modification illustrated in Fig. 12 of the drawings, the construction is similar 45 to the above described construction excepting that the hood is formed integral with the burner tube.

In the modification illustrated in Fig. 13, the hood consists in a body forming the top 50 thereof and having the gutters 14 and ridges 15, but having the legs formed of wires 12^a. In such a construction the grease or juices must follow the wires instead of the gutters 13 in the legs 12. Where legs 12 with gutters 13 are provided, the grease will follow 55 the gutters 13 as indicated at *m* in Fig. 14, while when wires 12^a are used for the legs, the liquid will follow the wires as indicated at *n* in Fig. 14. It will be seen that with the 60 gutters the surface of the grease is less exposed to the action of the heat than where wires are used.

With any of the above constructions, it will be seen that the orifices are protected 65 from the contact of the grease or juices there-

with, avoiding the possibility of clogging the orifices and interfering with the operation of the burner. At the same time, these greases or juices, being confined to particular paths, are prevented from coming into such 70 proximity of the flames as would cause their ignition. Thus, it is rendered possible to broil the articles by placing them over the burners without interfering with the operation of the burners or burning the products 75 obtained from the articles broiled, which may be saved and which are valuable. The preferred construction, as first described, is particularly advantageous since it allows the hood or shield to be removed from the burner 80 proper, permitting the burner, as well as the hood or shield, to be thoroughly cleaned. The advantages attendant upon broiling the articles over the burners instead of under them, as is generally practiced, will be obvious, since, in attempting to direct the heat 85 downward onto the articles, as ordinarily, most of the heat is wasted.

As illustrated in Fig. 4, it will be seen that the size of the broiler may be increased to 90 any desired extent with the use of the hood as a unit, using these units in any desired number, placing them one after the other, with their ends abutting, along the burner tube, and clamping them in position thereon 95 in the usual manner. Thus, as shown in Fig. 4, the burner is long enough to receive two of the hoods thereon, allowing the broiling space of the broiler to be practically twice the extent of that of the broiler illustrated in Fig. 1 of the drawings. It will be noted that the arches constituting the hood are not only arched over the orifices of the burner but are arched over the burner transversely thereof so that the tops of the arches 105 afford the most efficient means for conducting the grease laterally of the burner and down past the sides thereof, but the bottoms or interior parts of the arches of the hood are separate from the burner tube far enough to afford ample air space between these parts of the hood and the adjacent parts of the tube to avoid undue heating of the hood as hereinbefore referred to. In addition to 110 thus affording insulation of the hood from the burner, such a construction renders the hood less liable to warp under the action of the heat, since it substantially consists in a series of concavo-convex shells integral with each other, these shells being concave and 115 convex both transversely of the hood and longitudinally thereof.

As illustrated in Fig. 1, the casing 1 may be provided with a shelf 20 upon which articles may be placed for warming, thus utilizing 120 the heat that escapes upward past the broiler grating. In this connection it may be noted that whereas in the broiler with the burners over the broiler grating most of the heat will naturally be directed upward in- 125 130

stead of onto the article to be broiled so that a shelf, such as the shelf 20, over such a broiler would receive most of the heat, in my improved broiler only such heat as escapes 5 past the articles being broiled will be communicated to the warming shelf, utilizing most of the heat for broiling, which is the object sought to be attained by any broiler.

Having fully described my invention, what 10 I claim as new and desire to secure by Letters Patent is:

1. In a broiler, the combination with a burner having orifices for the escape and combustion of gaseous fuel, of a hood mounted on the burner having arches over said orifices through which the flames of combustion may pass from the orifices, and having extensions adjacent to the burner by means of which fluid matter is carried below the 20 burner without ignition.

2. In a broiler, the combination with a burner, of a hood having arches straddling the burner, substantially as and for the purposes herein set forth.

25 3. In a broiler, the combination with an elongated tubular burner, of a hood having arches straddling the burner, said arches being concavo-convex in the direction of the length of the burner and transversely there- 30 of, substantially as and for the purposes herein set forth.

35 4. In a broiler, the combination with a tubular burner, of a hood straddling said burner, and means for maintaining said hood in upright position thereon, substantially as and for the purposes herein set forth.

40 5. In a broiler, the combination with a tubular burner, of a hood straddling said burner and engaging means between the hood and the burner for holding the hood in upright position thereon, substantially as and for the purposes herein set forth.

45 6. In a broiler, the combination with a burner of elongated formation, of a hood straddling the burner along the length thereof, and means for adjusting said hood longitudinally of said burner and holding the hood in adjusted position thereon, substantially as and for the purposes herein set forth.

50 7. In a broiler, the combination with a series of burners extending adjacent to each other, of a hood on each burner, the burner and the hood being provided with openings for allowing the escape of the flames of combustion from the burner, and liquid conducting means on each of said hoods, the hoods on adjacent burners each having its liquid conducting means opposite the opening for the escape of the flames of combustion in the 55 other hood, substantially as and for the purposes herein set forth.

60 8. In a broiler, the combination with a burner, and a grating over the burner to support articles to be broiled, of a hood mounted 65 on the burner adapted to allow the passage

of the flames of combustion from the burner upward toward the articles to be broiled, and means on said hood for conducting greases from said articles away from said burner, substantially as and for the purposes herein set forth. 70

9. In a broiler, the combination with a burner, of a hood having an arch over the burner, and a vertically extending leg at the side of the burner, substantially as and for the purposes herein set forth. 75

10. In a broiler, the combination with a burner of elongated formation, of a hood comprising a unit mounted on said burner, and extending part of the length thereof and 80 another similar hood comprising another unit abutting against said first mentioned unit at one end and extending another part of the length of said burner, substantially as and for the purposes herein set forth. 85

11. In a broiler, the combination with a burner of elongated formation, of a hood in the form of a series of arches succeeding each other lengthwise of the burner and straddling the burner, said hood extending part of the 90 length of the burner, and another hood in form similar to the first mentioned hood having one end abutting against the end of the first mentioned hood and extending another part of the length of the burner, sub- 95 substantially as and for the purposes herein set forth.

12. In a broiler, the combination with a tubular burner having orifices extending radially through its walls, of a hood in the 100 form of a series of arches succeeding each other lengthwise of the burner and straddling the burner, each of said arches being so positioned that one of the orifices in the burner will be located within it and each of said 105 arches being arched over the tubular burner, whereby they are spaced away therefrom, substantially as and for the purposes herein set forth.

13. In a broiler, the combination with a 110 series of tubular burners extending parallel to each other, of a hood on each burner in the form of a series of arches succeeding each other longitudinally of the burner, the burner having orifices, and the arches of the hood 115 being positioned so that the orifices are within the arches, and liquid conducting means adjacent to where the arches succeed each other, said burners and the hoods thereon being so positioned that adjacent burners 120 will each have its orifice opposite to the liquid conducting means on the hood of the other burner, substantially as and for the purposes herein set forth.

14. In a broiler, the combination with a 125 tubular burner of elongated formation provided with a series of orifices extending upwardly in an inclined direction through its walls, a hood in the form of a series of arches succeeding each other lengthwise of the 130

- burner, and a leg thereon between each arch on each side of the burner, the hood having laterally downwardly sloping gutters between the arches communicating with said 5 legs, and the top of each arch being inclined toward said gutters, each one of said orifices being within each one of said arches, substantially as and for the purposes herein set forth.
- 10 15. In a broiler, the combination with a series of tubular burners of elongated formation extending parallel to each other, of a hood on each burner in the form of a series of arches succeeding each other lengthwise of the burner and straddling it, and a leg on the 15 hood between each arch on each side of the burner on which the arch is located, the burner having a series of orifices extending radially upwardly in an inclined direction 20 through its walls and one of said orifices being within each one of said arches, said hoods having gutters between the arches communicating with said legs and the hood being so positioned on its respective burner and the 25 orifice in each burner being so positioned, that adjacent burners will have their orifices opposite to the gutters in the hood on the other burner, substantially as and for the purposes herein set forth.
- 30 16. In a broiler, the combination with a burner, of a hood in the form of a series of arches succeeding each other lengthwise of the burner and straddling the burner, and legs on the hood between each arch on each 35 side of the burner, the hood having gutters between the arches communicating with the legs and each arch having a horizontal middle ridge from which the top of said arch inclines in both directions to the gutters between it 40 and the adjacent arches, substantially as and for the purposes herein set forth.
17. In a broiler, the combination with a burner having orifices for the escape and combustion of gaseous fuel, of a hood on the
- burner forming a shield over the orifices, said 45 hood being removable from said burner, substantially as and for the purposes herein set forth.
18. In a broiler, the combination with a tubular burner of elongated formation, of a 50 hood having legs at each side of the burner, the burner having orifices between said legs and the hood being adapted to form a shield over said orifices, substantially as and for the 55 purposes set forth.
19. In a broiler, the combination with a tubular burner, of a hood on the burner, and legs on the hood at the sides of the burner, the legs having gutters, the burner having orifices between the legs, and the hood being 60 adapted to form a shield over the burner and having gutters to conduct fluid into the gutters in the legs, substantially as and for the 65 purposes herein set forth.
20. In a broiler, the combination with a tubular burner, of a hood in the form of a series of arches succeeding each other lengthwise of the tube and straddling the tube, legs 70 on the hood between the arches, the hood having gutters between the arches communicating with the legs and each arch having a middle horizontal ridge extending transversely of the hood and having its top inclined from the ridge in both directions to the gutters, and each of said arches being 75 concave on its under side adjacent to the burner longitudinally of said burner and transversely thereof, whereby the lower side of the arch is spaced away from the burner, the burner having orifices within the arches 80 between the legs, the arches of the hood being adapted to form a shield over the orifices of the burner, substantially as and for the purposes herein set forth.

LOUIS FEY.
